US0D1016029S

(12) **United States Design Patent** (10) Patent No.: **US D1,016,029 S**
Lee et al. (45) Date of Patent: ** Feb. 27, 2024

(54) **ELECTRONIC DEVICE**

(71) Applicant: **Samsung Electronics Co., Ltd.**, Suwon-si (KR)

(72) Inventors: **Ji-Young Lee**, Suwon-si (KR); **Hyok-Su Choi**, Suwon-si (KR); **Chung-Ha Kim**, Suwon-si (KR); **Jong-Bo Jung**, Suwon-si (KR); **Min-Young Park**, Suwon-si (KR)

(73) Assignee: **SAMSUNG ELECTRONICS CO., LTD.**, Suwon-si (KR)

(**) Term: **15 Years**

(21) Appl. No.: **29/850,647**

(22) Filed: **Aug. 22, 2022**

Related U.S. Application Data

(62) Division of application No. 29/729,153, filed on Mar. 24, 2020, now Pat. No. Des. 974,342.

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the figures illustrate portions of the electronic device that form no part of the claimed design. The dot-dash broken lines in FIGS. 1-3 and 6-9 define a claim boundary only and form no part of the claimed design.

1 Claim, 8 Drawing Sheets
